(57) **CLAIM**

The ornamental design for a showerhead, as shown and described.

DESCRIPTION

In a preferred embodiment, the nature of this product is as a plumbing fixture in the form of a showerhead primary useful for washing body parts.

FIG. 1 is a left, top, front perspective view of a showerhead according to our new design;

FIG. 2 is a front elevational view thereof;

FIG. 3 is a top plan view thereof;

FIG. 4 is a left side elevational view thereof, the right side elevational view thereof being a mirror image of the left side shown; and,

FIG. 5 is a rear elevational view thereof.

The broken line showing is for illustrative purposes only and forms no part of the claimed design.
